UNITED STATES PATENT OFFICE.

HAROLD EDGAR YARROW, OF SCOTSTOUN, GLASGOW, SCOTLAND.

CONSTRUCTION OF SUBMARINE VESSELS.

1,229,004.

Specification of Letters Patent. Patented June 5, 1917.

Application filed August 1, 1916. Serial No. 112,612.

To all whom it may concern:

Be it known that I, HAROLD EDGAR YARROW, a subject of the King of Great Britain, residing at Scotstoun, Glasgow, Scotland, have invented certain new and useful Improvements in the Construction of Submarine Vessels, of which the following is a specification.

In the construction of a submarine vessel difficulties occur owing to the confined space in which the men have to work, which limits the number who can be employed and also hampers their operations, and for both reasons, prolongs the time required for the construction of the vessel.

These drawbacks apply more especially to the operations of riveting and of making the water-tight connections between the hull and the various tanks into which a submarine vessel is subdivided.

In the usual practice, the hulls of these vessels are formed, as in ships not intended for submersion, of transverse frames to which the plates are connected, and in the confined space of a submarine a very considerable amount of time is required to make and to rivet in place the special water-tight filling-in pieces, where these frames pass through a water-tight, flat or bulkhead.

The principles determining the construction of an ordinary sea-going ship do not apply without modification to a submarine vessel which is usually of the approximate form of a tube of annular cross section. The principal stress to which a submarine is exposed is due to the external pressure exerted by the column of water, and it is well known that an annular section is best adapted to withstand such pressure and that, for a given amount of material, a tube is best adapted to give the longitudinal strength to resist bending moments.

According to the invention, the hull of a submarine vessel of the type mentioned is formed of external plates connected by longitudinal and transverse butt straps adapted without the addition of transverse frames to stand the stresses to which the structure is normally subjected.

If a submarine should rest on the bottom of the sea and should happen to lodge on a sharp rock, or on a pointed object, such as an anchor, the transverse frames become a source of weakness, since they localize the extent to which the plating can give way in order to accommodate itself to the ob-

struction. The indentation is consequently very local and the plating is liable to be ruptured and allow water to find access to the interior of the vessel.

In the arrangement according to the invention, all or some of the plates are flanged for the attachment of the various fittings to the interior in order to avoid the drawbacks attending the provision of rivets passing through the hull. This flanging also adds to the stiffness of the structure but is not required to supply the resistance to the bending moments or the external pressure.

The material saved by the omission of the transverse frames may be put into the external plating and thereby strengthen the vessel against local damage.

In the accompanying drawings, which illustrate diagrammatically an example of a construction of a submarine vessel according to the invention, Figure 1 is a transverse section about midships;

Fig. 2 is a transverse section where the outer hull is in direct communication with the inner hull;

Fig. 3 is a longitudinal section through the vertical center line of Figs. 1 and 2;

Fig. 4 shows a portion of the plating with the longitudinal and transverse butt straps.

The plates *a* form the internal hull; the plates *b* form the external hull or ballast tanks, which extend over the greater part of the length of the vessel. In the example shown, every other plate of the inner hull is provided with a flange *c* at each edge, and every other plate of the outer hull with a flange *d* at each edge, but every plate may be flanged at one or both edges. The plates *a* are connected by longitudinal butt straps *e*. Below the water-tight flat *f* are the oil fuel and ballast tanks. Where there is a large opening in the inner hull extra stiffening members *g* may be provided. The transverse butt straps *h* (Fig. 4) may be flanged at each end, as shown, in order to make a particularly strong connection with the plates *a*.

Having thus described my said invention and the best means I know of carrying the same into practical effect, I claim:

1. In a submarine vessel, of the type in which the hull is approximately in the form of a tube of annular cross section, external plates connected by longitudinal and transverse butt straps adapted to sustain, without the addition of transverse frames, the bend-

- 2
- ing moments and external pressure to which the vessel is exposed, substantially as described.
2. In a submarine vessel, of the type in which the hull is approximately in the form of a tube of annular cross section, external plates connected by longitudinal and transverse butt straps adapted to sustain, without the addition of transverse frames, the bending moments and external pressure to which the vessel is exposed, the ends of at least some of the plates being bent inward in order to provide for the attachment of the various fittings to the interior of the vessel without the provision of rivets passing through the hull, substantially as described.

3. In a submarine vessel, of the type in which the hull is approximately in the form of a tube of annular cross section, external plates connected by longitudinal and transverse butt straps which are flanged at each end and are adapted to sustain, without the addition of transverse frames, the bending moments and external pressure to which the vessel is exposed, substantially as described. 20 25

In testimony whereof I have signed my name to this specification in the presence of two subscribing witnesses.

HAROLD EDGAR YARROW.
